UNITED STATES PATENT OFFICE.

CLIFFORD BARGAMIN, OF NEWPORT NEWS, VIRGINIA, ASSIGNOR TO NOVELTY MANUFACTURING CORPORATION, OF NEWPORT NEWS, VIRGINIA, A CORPORATION OF VIRGINIA.

MECHANIC'S FURNACE.

No. 862,958.

Specification of Letters Patent.

Patented Aug. 13, 1907.

Application filed May 2, 1906. Serial No. 314,840.

To all whom it may concern:

Be it known that I, CLIFFORD BARGAMIN, a citizen of the United States, residing at Newport News, in the county of Warwick and State of Virginia, have invented a certain new and useful Mechanic's Furnace, of which the following is a specification, reference being had therein to the accompanying drawing.

This invention relates to mechanic's furnaces, the object of the invention being to simplify and improve the construction set forth in my prior patent No. 826,083, dated July 17, 1906, to the end that a separate heating compartment or chamber is provided for each soldering iron or other form of iron to be heated, a separate and independent burner or blast being employed for each compartment or chamber and used in connection with appliances hereinafter particularly described whereby each compartment or chamber and burner is rendered independent of the other or others so that when an iron is removed from one heating chamber, the main supply of gas or other fluid will be cut off from that particular heating chamber without affecting any other, thus economizing in the consumption of gas.

A further object of the invention is to provide novel means for regulating the maximum supply of gas to each individual heating chamber and locking the regulating device whereby only a certain predetermined amount or quantity of gas is fed to the burner or blast when the connections which control the gas supply valve are put in operation by placing the iron in its respective compartment or heating chamber.

A further object of the invention is to provide a novel arrangement of air and gas pipes in connection with the gas valves and air valves whereby the gas and air are mixed in the proper quantities and the mixture conducted to the several burners.

Actual tests have demonstrated the fact that by the use of the improved mechanic's furnace to be herein described, a saving of approximately 50% of gas is effected by reason of the compartments or heating chambers being isolated from each other and providing means whereby the flame is extinguished in any compartment or chamber from which the iron is removed, the burner being reignited only when the iron is replaced in such chamber or compartment.

With the above and other objects in view, the nature of which will more fully appear as the description proceeds, the invention consists in the novel construction, combination and arrangement of parts as hereinabove fully described, illustrated and claimed.

In the accompanying drawings: Figure 1 is a front elevation of a mechanic's furnace embodying the present invention. Fig. 2 is a rear elevation of the same. Fig. 3 is a vertical fore and aft section through the fur-

nace. Fig. 4 is an enlarged vertical sectional view of the economizer or gas-supply valve, and Fig. 5 is an enlarged detail sectional view illustrative of the gas-supply regulating device.

In carrying out the present invention, the body 1 of the furnace is divided by one or more partitions 2 into a plurality of heating compartments or heating chambers 3 each of which is independent of and isolated from the other, each compartment being closed on all sides with the exception of the front of the furnace where the compartment is left open as shown in Figs. 1 and 2.

In the top of each chamber or compartment 3 is a blast-hole 4 immediately above which is a burner 5 with the upper end of which is connected an air-supply pipe 6 while connected to the burner at a point between its extremity and the air-supply pipe 6 is a gas-supply pipe 7. The pipes 6 and 7 extend downward behind the furnace as shown in Figs. 2 and 3, the air-supply pipe 6 connecting with the main air-supply pipe 8 while the gas pipes 7 lead to the outlet nozzles 9 of a corresponding number of economizer or gas-supply valves 10 each of which communicates at its opposite side through an inlet nozzle 11 with a main supply gas pipe 12 which extends beneath the air pipe 8 and parallel thereto as shown in Fig. 2. The pipes 8 and 12 are connected together and relatively braced at suitable points by connecting nipples 13. These nipples are solid or plugged, however, so as to prevent the air and gas communicating and mixing until the same have been conducted to a point adjacent to the burners 5. Each air pipe 6 is provided with a separate and independent valve or cock 14 whereby the supply of air may be regulated to suit the gas-supply.

Each economizer or gas supply valve is of the construction illustrated in detail in Fig. 4 in which it will be observed that the inlet and outlet nozzles 11 and 9 extend in opposite directions from the main casing 15 of the valve. This casing is provided with a tapered bore in which is fitted the main valve 16 having a taper corresponding with the inside of the casing, and held in place therein by a screw plug 17 between the head of which and the bottom of the casing 15 is interposed a washer 18. Within the top of the valve 16, which is hollow, is inserted a hollow screw cap 19 which secures a diaphragm 20 against an annular shoulder formed inside of the valve and which forms a tight joint and prevents any possibility of the escape of gas during the manipulation of the inner auxiliary valve which is shown at 21, the same being movable up and down and normally bearing against an internal valve seat 22 so as to prevent the gas from passing from the inlet nozzle 11 to the outlet nozzle 9.

The auxiliary valve 21 is provided with an upwardly extending stem 23 which is securely clamped to the diaphragm 20 and extends upward through an opening in the cap 19 above which said stem is provided with a head or collar 24 adjustably mounted and held thereon by a binding screw 25.

- Each economizer or gas-supply valve is operated automatically by a lever 26 which extends under the bottom of the furnace as shown in Fig. 3 and is provided with a journal or shaft portion 27 mounted in one or more bearings 28 extending upward from the valve casing 15 as shown in Fig. 4. The shaft or journal portion 27 has an off-standing lever arm 29 which projects beneath the head or collar 24 so that when the shaft 27 turns in one direction, said lever arm 29 lifts on the collar 24 and unseats the auxiliary valve 21, allowing the gas to pass to the burner. When the shaft 27 turns in the opposite direction, the valve 21 is returned to its seat and held closed by means of a spring 30.
- 20 The forward end of each lever 26 is extended upward to form an arm 31 and on the upper end of said arm is mounted a saddle 32 upon which the handle of a soldering iron or other form of iron is adapted to rest as shown in Fig. 3 while the iron is being subjected to the flame or blast from the burner 5. The saddle 32 is preferably dished or concaved as shown, and has an adjustable connection with the arm 31, the saddle being for that purpose provided with a downwardly extending stem or post 33 which is hollow and internally threaded 25 as shown in Fig. 5 to receive the threaded upper end of the arm 31. The stem or post 33 of the saddle slides up and down through a stationary rest 34 in the form of a leaf or shelf projecting from the front of the furnace and provided with openings 35 through which the stems or 30 posts 33 of the several levers 26 move. The rest 34 forms a ledge upon which to rest the irons when not in use, it also forms a guide for the stems or posts 33, and also a supporting stop for the saddles 32, the downward movement of which is limited by said stationary rest 34.
- 40 It will now be observed that the more movement that is allowed the saddle 32, the more movement there will be for the shaft 27 and the greater the movement of the valve 21; therefore by adjusting a saddle 32 upward or downward on its respective arm 31, the amount of the 45 movement of said saddle may be regulated and thereby the amount of gas which is allowed to pass by the auxiliary valve 21 to the burner. In order to lock each saddle 32 and prevent a mechanic from unduly increasing the flow of gas, I provide locking means, which, in the preferred embodiment of the invention, embodies a locking pin 35 insertible through an opening in the saddle and provided at its upper end with a head 36 to hold the same in place. The pin 35 extends downward through a corresponding hole 37 in the stationary rest

and is provided at its lower end with an eye 38 to receive a pad-lock 39 or its equivalent which prevents the locking pin 35 from being withdrawn and the adjustment of the saddle being tampered with.

40 designates a pilot tube which leads from an outlet opening 41 in the valve to a point adjacent to its respective burner 5 so as to maintain a small flame adjacent to the main burner when the flow of gas is cut off therefrom by removing the soldering iron from the furnace and releasing the saddle 32 and connections which close the auxiliary valve 21.

42 designates the main valve handle by means of which the main valve may be turned to throw the ports thereof out of alinement with the inlet and outlet nozzles to entirely cut off the supply of gas.

I claim:

1. A mechanic's furnace comprising a plurality of separated independent heating chambers, a burner for each chamber, a gas supply pipe leading to said burner, a valve controlling said pipe, a valve operating lever, a saddle carried by and adjustably mounted on said lever, and means coöperating with said saddle to limit the movement of the lever, substantially as described.

2. A mechanic's furnace embodying a heating chamber, a burner therefor, a gas supply pipe leading to the burner, a valve controlling said pipe, a valve actuating lever, a saddle adjustably connected to said lever, and means coöperating with said saddle to limit the movement of the said lever substantially as and for the purpose described.

3. A mechanic's furnace embodying a heating chamber, a burner therefor, a gas supply pipe leading to the burner, a valve controlling said pipe, a valve actuating lever, a saddle adjustably connected to said lever, and a stationary supporting rest for said saddle, whereby the movement of the saddle is limited in one direction.

4. A mechanic's furnace embodying a heating chamber, a burner therefor, a gas supply pipe leading to the burner, a valve controlling said pipe, a valve actuating lever, a saddle adjustably connected to said lever, and means for locking said saddle.

5. A mechanic's furnace embodying a heating chamber, a burner therefor, a gas supply pipe leading to the burner, a valve controlling said pipe, a valve actuating lever, a saddle adjustably connected with said lever, a stationary rest forming a support for the saddle, and saddle locking means embodying a pin insertible through openings in the saddle and stationary rest, and a device to prevent the withdrawal of said pin.

6. A mechanic's furnace embodying a heating chamber, a burner therefor, a gas supply pipe leading to the burner, a valve controlling said pipe, a valve actuating lever, a saddle having an adjustable and threaded connection with said lever, a stationary rest through which a portion of the saddle is movable, and locking means engaging the saddle and stationary rest to prevent turning the saddle, substantially as described.

In testimony whereof I affix my signature in presence of two witnesses.

CLIFFORD BARGAMIN.
